UNITED STATES PATENT OFFICE.

JOSEPH D. CARPENTER, OF PROVIDENCE, RHODE ISLAND, ASSIGNOR TO
JAMES B. RICHARDSON, OF SAME PLACE.

DETACHABLE BUTTON.

SPECIFICATION forming part of Letters Patent No. 242,881, dated June 14, 1881.

Application filed April 1, 1881. (No model.)

To all whom it may concern:

Be it known that I, JOSEPH D. CARPENTER, of Providence, in the State of Rhode Island, have invented an Improvement in Detachable Buttons, of which the following is a specification.

My invention relates to that class of detachable buttons where the shoe is hinged to the post, and held in proper position for holding the button or inserting the shoe in the button-hole by means of a spring arranged in the shoe; and my invention consists in the improved construction of the hinge-joint between the post and shoe.

Figure 1 represents a central vertical section taken in the line of the flat side of the post. Fig. 2 represents a central vertical section taken in the line xx of Fig. 1. Fig. 3 represents an elevation of the head of the button, with a section of the shoe in the line of the side of the post. Fig. 4 represents the head of the button in elevation, with a central section of the post and shoe, as in Fig. 2. Fig. 5 represents a plan view of the inner plate of the shoe. Fig. 6 represents a section of the same, taken in the line zz of Fig. 5. Fig. 7 represents a section taken in the line xx of Fig. 5. Fig. 8 represents a side elevation of the post. Fig. 9 represents a section of the same, taken in the line xx of Fig. 8. Fig. 10 represents a plan view of the spring which serves to operate the shoe.

In the accompanying drawings, A is the head of the button, and B a flat post, provided with a transverse slot, b, and either having

its end c bent at an angle with the body of the post or otherwise made square, with a flattened lower surface for the action of the spring. The shoe C is provided with an inner plate, D, made with a semi-cylindrical indentation, 40 g , and with the two slotted openings aa , thus forming the tongue d , provided with a curve at its base. An indentation, e , is also made in the plate D to receive the spring E.

The tongue d being passed through the slot 45 b of the post, so that the curved base of the tongue may rest in the slot, and the spring E being arranged in the shoe so as to press against the inclined end c of the post B, then the spring E will cause the shoe to be held 50 firmly, both in its position for entering the button-hole, as shown in Figs. 1 and 2, and for holding the button after insertion, as represented in Figs. 3 and 4, the slotted post B and the tongue d serving as a cheap and efficient means for properly attaching the shoe C. The bottom h of the slots aa serve as stops 55 against the side of the post to hold the shoe firmly when in its locking position.

I claim as my invention—
In a button, the combination of the post B, provided with a transverse slot, b, with the hinge-plate D, provided with the tongue d , adapted to the slot b , and the spring E, arranged to operate upon the flattened lower end 60 of the post, substantially as described.

JOSEPH D. CARPENTER.
